PIPE UNSCREWING SOCKET

Filed Oct. 19, 1927

UNITED STATES PATENT OFFICE

FRANK J. HINDERLITER, OF TULSA, OKLAHOMA

PIPE-UNSCREWING SOCKET

Application filed October 19, 1927. Serial No. 227,196.

The present invention has to do with means for removing pipe sections from a well, and more particularly to a device which may be termed an unscrewing socket adapted to embrace a section of pipe in a well casing, whereby this section may be unscrewed and disconnected from the lowermost sections.

An object of the present invention resides in the provision of a socket adapted to be lowered in a well casing without disturbing the string of piping therein and adapted to embrace one of the sections comprising said string, whereby this section may be unscrewed from the section immediately therebelow.

Another object of this invention is the provision of an unscrewing socket for well piping including a milling surface adapted to mill its way over the end of the upper section of piping, whereby the socket will slide downwardly over the piping.

A further object of the invention is the provision of an unscrewing socket for well piping having its lower end provided with a plurality of teeth adapted to bite into the top edge of the uppermost coupling, whereby this coupling may be removed from the well with the section of piping disposed thereabove.

A still further object of my invention has to do with the provision of an unscrewing socket for well piping including an eccentric wedge having a toothed surface adapted to bite into the wall of the section of pipe to be removed from the well.

Other objects and advantages of my invention will more fully appear from the following detailed description taken in connection with the accompanying drawing, which illustrates several embodiments thereof and in which:

Figure 1 is a fragmentary vertical sectional view through a well casing and the socket of my invention showing the socket in cooperation with a section of piping to be removed from the casing;

Figure 2 is an enlarged cross-sectional view taken through my novel socket on substantially the line II-II of Figure 1 looking downwardly and showing the position

of the slip or wedge prior to the unscrewing operation;

Figure 3 is a cross-sectional view similar to Figure 2 illustrating the position of the wedge after the socket has been turned in the direction indicated by the arrow;

Figure 4 is a cross-sectional view similar to Figure 3 illustrating a slip adapted for use in connection with piping having left hand threads and showing the position of the slip when the socket is turned in the direction indicated by the arrow;

Figure 5 is an enlarged vertical sectional view through the socket of my invention;

Figure 6 is a bottom end view of the socket;

Figure 7 is a vertical sectional view through a modified form of socket adapted to be lowered inside of the piping to be removed from the well;

Figure 8 is a cross-sectional view through this modified form of socket showing it applied to a pipe drawn to a reduced scale, and

Figure 9 is a bottom end view of the socket shown in Figure 7 drawn to a reduced scale.

In the drawings, like reference characters designate similar parts throughout the several views.

The reference character 10 designates generally the socket of my invention which comprises a tubular body 11 having its upper end provided with a threaded countersunk opening 12 adapted to have threaded therein the lower reduced end 14 of a bowl or tube 13. This bowl has an annular tapered slip seat 15 adapted to accommodate a plurality of slips 16 secured to lowering reins 17. These slips, as will be more fully explained hereinafter, are adapted to be lowered by means of the reins 17 into the space between the annular seat and the pipe section 18, whereby the pipe section 18 may be rigidly anchored to the socket 10, thus enabling this pipe section and the socket to be removed together from the well casing 19.

The upper end of the pipe section is shown as being broken and provided with a ragged or rough edge 20. The lower end of this section 18 is threaded into the top of a pipe coupling 21 which has also threaded into it a lower pipe section 22. In Figure 1 the

socket 10 is shown in a position ready to disconnect the pipe coupling 21 from the pipe section 22, whereby the section 18 and the coupling 21 may be withdrawn from the casing 19.

The lower end of the socket body 11 is countersunk, as indicated at 24. The surface of this end of the body defining the countersunk opening is provided with a ring 10 of teeth 25. These teeth are made of such a shape and form as to in reality comprise a mill, the purpose of which will be more fully explained hereinafter.

An intermediate portion of the body 11 is provided with an elongated eccentric slot 26 (Figures 2 and 5). This slot is of a dovetail shape and is adapted to receive an arcuate-shaped slip or wedge 27. The slip 27 has a dovetail cross-section so as to enable it to be slidably mounted in slot 26. It will be noted that the slot 26 and the wedge 27 are disposed in the inner surface of the tubular body 11. Also attention is directed to the fact that the slot 26 is of a larger size than the arcuate-shaped slip 27, as is best shown in Figure 2. The inner surface of the slip 27 is provided with a plurality of teeth 28 adapted to frictionally engage the outer surface of the pipe section disposed therein. Also the slip 27 is prevented from being displaced from the slot during the unscrewing operation by means of the two pins 29 which are mounted in the body 11 and extend into the opposite extremities of the eccentric slot 26.

The operation of the preferred form of my invention is briefly as follows:

The tubular body 11 is first coupled to the tubular member 13 which is in turn secured to a suitable string of pipe 9 adapted to be used to lower the socket into the well casing 19.

Upon the teeth on the lower end of the body 11 coming into the vicinity of the broken end 20 of pipe section 18, they will function to mill away any projections extending outwardly from this end, whereby the body member 11 can slide readily over the pipe 18. Also these teeth will bite into the upper edge of the coupling 21 so as to enable the socket to unscrew the coupling from the lower pipe section 22. This means that both the coupling 21 and the broken pipe section 18 will be removed together from the casing.

Obviously after the teeth 25 have engaged the coupling 21, the socket 10 may be rotated to unscrew the coupling. The slip 27 during this rotation of the socket will bite tighter into the outer surface of the pipe section 18 and thus prevent a relative movement between the socket and this pipe section. Thereafter the slips 16 may be lowered into the well by means of the reins 17 until they are seated upon the annular shoulder 15. When thus positioned, each of these slips 16

serves to wedge the pipe section 18 to the bowl or tubular member 13, whereby the same may be withdrawn from the casing with the socket 10.

In Figure 4 I have illustrated a modification of the invention wherein the slip 27^a is provided adapted for use in connection with pipes having left hand threads. It will, of course, be apparent that in order to remove the pipe section, it will be necessary to rotate the socket in a clockwise direction, whereas in the construction shown in Figure 3 it was necessary to rotate the socket in a counter-clockwise direction due to the fact that that construction was especially adapted for use in connection with pipes having right hand threads.

In Figures 7, 8 and 9 I have illustrated a modification of my invention adapted to be lowered inside of the pipe section to be removed. This socket comprises a tubular member 11' having a threaded opening 12' adapted to receive a bowl or tubular member such as the member 13. The outer surface of this tubular member 11' is provided with an eccentric vertical slot 26' designed to receive an arcuate-shaped slip or wedge 27' having its outer surface provided with a plurality of teeth 28'. This slip 27', like the slip 27, has a dovetail cross-section, whereby it will not gravitate from the slot 26' which is also of a dovetail construction. The slip 27' is held against lateral displacement from the slot 26' by means of the pins 29' mounted in the body 11'.

The lower end of the body 11' is tapered, as indicated at 24', and is provided with a plurality of slanting teeth 25' adapted to mill any projections from the inside wall of the pipe section such as the pipe section 18 during the time it is being lowered therein.

In Figure 8 I have illustrated the socket 11' as being disposed inside of a pipe section 18', both the device and the pipe section being shown in cross-section. It will be evident that the teeth 28' of the wedge or slip 27' will, upon the turning of the body 11' of the socket, bite into the internal surface of the pipe section 18, whereby the section will turn with the body 11'. This modification of my invention is not as desirable as the preferred form, inasmuch as it will not remove the pipe coupling with the pipe section, as is the case with the construction shown in Figure 1.

I desire it understood that although I have illustrated and described in detail the preferred forms of my invention, the invention is not to be thus limited, but only in so far as defined by the scope and spirit of the appended claims.

I claim as my invention:

1. In a device for unscrewing pipe and the like, a body member having a bore slightly larger than a pipe to be engaged and com-

5 municating with an arcuate-shaped slot formed in its surface, an arcuate-shaped slip mounted in said slot and arranged for movement in said slot about the axis of said body member so that upon the rotation of the body member it will move further into said bore to wedge the pipe to the body member, whereby the pipe may be turned therewith and additional gripping means for engaging said

10 pipe in a longitudinal direction.

2. In a device for unscrewing pipe and the like, a body member having an arcuate-shaped slot formed in an intermediate portion thereof, a slip mounted in said slot in such a manner as to prevent its lateral displacement therefrom, said slip being arranged to move in said slot about the axis of the body member, whereby it will wedge a pipe to the body member to permit of the

20 pipe being turned therewith and additional gripping means for engaging said pipe in a longitudinal direction.

3. In a device for unscrewing pipe and the like, a body member having a slot formed in the surface thereof, a slip mounted in said slot in such a manner as to prevent its lateral displacement therefrom, said slip being movable in said slot about the axis of the body member, whereby it will wedge a pipe to the body member to permit of the pipe being turned therewith, and means associated with the lower end of the body member for biting into a coupling on the pipe to be unscrewed so as to permit of the coupling being removed

35 with the pipe.

4. In a device for unscrewing pipe and the like, a tubular body member adapted to be slid over the pipe to be unscrewed, said body member having a slot formed in its internal surface and a slip in said slot for wedging said member upon rotation thereof to said pipe, whereby the pipe will turn therewith, said body member having its upper end formed on a slant to receive a slip for wedging the pipe to the body member.

5. In a device for unscrewing pipe and the like, a tubular body member adapted to be slid over the pipe to be unscrewed, said body member having a slot formed in its internal surface and a slip in said slot for wedging said member upon rotation thereof to said pipe whereby the pipe will turn therewith, said body member including a bowl member having an annular seat formed to accommodate a plurality of slips for rigidly wedging the bowl member to the pipe upon the upward movement of the tubular member.

6. In a device for removing a pipe section from a well casing and the like, a tubular member adapted to be lowered into the casing over the pipe section to be removed, a slip associated with the inner surface of the tubular member for wedging said member upon rotation thereof to the pipe section so that the

means comprising milling teeth formed upon the lower end of the tubular member for milling any projections from the pipe section during the lowering of the tubular member thereover and also arranged to bite into the upper edge of the coupling associated with the lower end of the pipe section, whereby the coupling can be unscrewed with the pipe section.

7. In a device for removing a pipe section from a well casing and the like, a tubular member adapted to be lowered into the casing over the pipe section to be removed, a slip associated with the inner surface of the tubular member for wedging said member upon rotation thereof to said pipe section so that the pipe section may be rotated therewith and means comprising milling teeth formed upon the lower end of the tubular member for milling any projections from the pipe section during the lowering of the tubular member thereover and also arranged to bite into the upper edge of the coupling associated with the lower end of the pipe section, whereby the coupling can be unscrewed with the pipe section, said tubular member having a slanting surface for accommodating a plurality of slips adapted upon the upward movement of said member to rigidly wedge the pipe section thereto so as to allow the pipe section to be withdrawn with the tubular member.

8. In a device for removing a pipe section from a well casing and the like, a tubular member adapted to be lowered into the casing over the pipe section to be removed, a slip associated with the inner surface of the tubular member for wedging said member upon rotation thereof to the pipe section so that the pipe section may be rotated therewith, and means comprising milling teeth formed upon the lower end of the tubular member for milling any projections from the pipe section during the lowering of the tubular member thereover and also arranged to bite into the upper edge of the coupling associated with the lower end of the pipe section, whereby the coupling can be unscrewed with the pipe section, said slip comprising an arcuate member having a dovetail cross-section and being mounted in a dovetail slot in said body member.

9. In a device for unscrewing pipe and the like, a body member having a slot formed in a surface thereof, a slip mounted in said slot in such a manner as to prevent its lateral displacement therefrom, said slip being arranged to move in said slot about the axis of the body member, whereby it will wedge a pipe to the body member to permit of the pipe being turned therewith, means extending into said slot to prevent said slip from moving out of said slot and wedge means associated with said body member for wedgingly engaging said pipe in a longitudinal direction.

10. In a device for unscrewing pipe and the like, a body member having a slot formed in a surface thereof, a slip mounted in said slot in such a manner as to prevent its lateral displacement therefrom, said slip being arranged to move in said slot about the axis of the body member, whereby it will wedge a pipe to the body member to permit of the pipe being turned therewith, means extending into said slot to prevent said slip from moving out of said slot, said latter means including a plurality of spaced pins mounted in said body member and extending into said slot, and wedge means associated with said body member for wedgingly engaging said pipe in a longitudinal direction.
11. In a device for unscrewing pipe and the like, a body member, and wedge means connected to said member for wedging the body member to a pipe section to be unscrewed, said body member having its lower end provided with teeth for engaging a coupling on said pipe section.
12. In combination in a device for engaging pipe or the like, a body member, and wedge means connected to said member for wedging the body member to a pipe section, said body member having its lower end provided with means for frictionally engaging a coupling on said pipe section.

13. The method of unscrewing and removing a pipe section including a coupling member from a length of pipe in a well which consists in wedgingly engaging the pipe section in a radial direction so as to rotate and unscrew said section from an adjacent section, contemporaneously and frictionally gripping the coupling member to permit of its rotation with said pipe section and thereafter wedgingly engaging the pipe section in a longitudinal direction to remove it from the well.

In testimony whereof I have hereunto subscribed my name at Tulsa, Oklahoma, county of Tulsa.

FRANK J. HINDERLITER.
